210,389

TOY ANIMAL FIGURE OR THE LIKE

Kenneth L. Gillibrand, 13 Rudd Road, Illovo, Johannesburg, Transvaal, Republic of South Africa

Filed Feb. 15, 1966, Ser. No. 1,051

Term of patent 14 years

Claims priority, application Republic of South Africa
Aug. 26, 1965

(Cl. D34—2)

I claim:

The ornamental design for a toy animal figure or the like, substantially as shown.
